UNITED STATES PATENT OFFICE.

BRUNO WESSELMANN, OF GÖTTINGEN, GERMANY.

BALL-CASTER.

SPECIFICATION forming part of Letters Patent No. 607,720, dated July 19, 1898.

Application filed December 3, 1896. Serial No. 614,326. (No model.) Patented in Germany November 6, 1896, No. 93,169, and in England November 20, 1896, No. 26,223.

To all whom it may concern:

Be it known that I, BRUNO WESSELMANN, a subject of the King of Prussia, German Emperor, residing at Göttingen, in the Province of Hanover, Kingdom of Prussia, Germany, have invented new and useful Improvements in Furniture-Casters, (for which I have obtained German Letters Patent No. 93,169, dated November 6, 1896, and British Letters Patent No. 26,223, dated November 20, 1896,) of which the following is a specification.

This invention relates to furniture-casters, and has for its object to provide an extremely simple, strong, and durable caster in which the friction shall be minimized and which shall be capable of being manufactured at slight cost; and it consists in the construction and arrangement of parts hereinafter described, and particularly pointed out in the claim following the description, reference being had to the accompanying drawings, forming a part of this specification, wherein—

Figure 1 is a vertical section of the caster with ball and secured by slipping onto the foot of the article of furniture. Fig. 2 is a horizontal section along xx , Fig. 1. Fig. 3 shows in vertical section a caster with plate attachment. Fig. 4 is a section along yy , Fig. 3. Fig. 5 shows a vertical section of a furniture-caster in which a roller is applied in place of a ball. Fig. 6 is a side elevation of Fig. 5.

The ball k , Figs. 1 and 2, rests over or chiefly over a contraction at the lower end of the tube r and travels on the friction-balls f , which by means of the loose cross u are held uniformly separated. The above-named parts are passed from above into the tube or housing r , and a plate p is then inserted as a bearing, which plate has a channelled rim, into which along its entire circumference the shell of the tube is pressed by suitable tools, as readily seen in the drawings. The entire assembling of the caster is thus effected in a very solid and simple manner.

If the upper end of the tube is kept somewhat longer, Fig. 1, it can serve for securing the caster to the furniture-foot m . If the caster is to be provided with an attaching-

plate b , Fig. 3, the latter can be slipped over or about the tube end and secured by spreading the latter by means of the correspondingly-thickened plate p .

In using a caster-roller l , Figs. 5 and 6, carried by the cross-axle o , sitting in the short tube-piece a , the inwardly-pressed rim of the tubular housing r extends about the rim of the cap t of the tubular piece, whereby the latter is held in the housing r . Upon said cap travel the friction-balls f , which are pressed against the bearing-plate p . This plate is provided below with a stud e , serving as a swivel-axis for the tube-piece a .

It is clear that the described arrangement of the new caster makes the latter cheap of manufacture, especially since for the tubular housing waste pieces of velocipede or bicycle factories can be used. Moreover, the caster becomes extremely durable, is of light weight, and obtains a graceful neat appearance.

What I claim as new, and desire to secure by Letters Patent, is—

As a new article of manufacture the herein-described furniture-caster consisting of a shell formed from a single piece of metallic tubing, a rotatable support arranged and retained therein, a round bearing-plate arranged in said tubing above the rotatable support and provided upon its periphery with a groove, a ball-spacing plate loosely arranged in said tubing between the bearing-plate and the rotatable support, antifriction-balls arranged in the recesses of said spacing-plate and having a rolling bearing on the rotatable support and bearing-plate, said tubing being pressed into the groove in the periphery of the bearing-plate to rigidly fix and hold the latter against end thrust, and the upper end of the tubing being extended above the said groove and constructed for attachment to an article of furniture, for the purpose specified.

In testimony whereof I have hereunto set my hand in the presence of two subscribing witnesses.

BRUNO WESSELMANN.
